ROTARY COMPRESSOR

Filed March 27, 1930

UNITED STATES PATENT OFFICE

JOHN R. PRICE, OF CHARLOTTESVILLE, VIRGINIA, ASSIGNOR TO McELROY-SHEPHERD LABORATORIES, INCORPORATED, OF CHARLOTTESVILLE, VIRGINIA, A CORPORATION OF VIRGINIA

ROTARY COMPRESSOR

Application filed March 27, 1930. Serial No. 439,318.

My present invention relates to fluid pumps or compressors of the rotary type, and contemplates, for its novel features, the provision of an improved structure in this type of pump or compressor, whereby pressure losses are avoided with the consequent increase of efficiency.

A further advantage lies in the provision of means, whereby the compressor or pump may be run at high speeds and deliver larger volumes of air or other fluid pumped at high pressures over a given period of time, than has heretofore been possible.

A further advantage lies in the means provided, whereby the blades of the rotor are held in contact with the pump-body walls by the air pressures developed by the running of the rotor, be the pressures high, or low, thus doing away with springs, as currently used.

A further advantage lies in the details of the rotor structure, whereby the foregoing is accomplished, in the simplicity of the housing structure, the porting thereof, and in the simplicity of other parts involved.

These and other capabilities will be apprehended as the herein disclosure proceeds, and it is obvious that modifications may be made herein without departing from the spirit thereof, nor the scope of the appended claims.

In the drawing,

Fig. 1 is a front end view in elevation of the device, looking from right to left in Fig. 2, with the cover, shown in Fig. 2 and Fig. 6, removed, to show the interior assembly;

Fig. 2 is a central sectional view taken on the line 2-2 of Fig. 1, looking in the direction of the arrows;

Fig. 3 is a side view in elevation of the rotor and blades, showing the latter in a horizontal position;

Fig. 4 is a front end view mainly in elevation and partly in section of the rotor and blades, looking from right to left in Fig. 3;

Fig. 5 is a perspective view of one of the blades, which are hereinafter more fully described;

Fig. 6 is an outside front view of the cover removed;

Fig. 7 is a side view thereof, looking from left to right in Fig. 6;

Fig. 8 is a fragmentary sectional view of the outlet port in the cover taken on the line 8-8, Fig. 6, looking in the direction of the arrows; and

Fig. 9 is a similar view of the inlet port, taken on the line 9-9, Fig. 6, looking in the direction of the arrows.

The air compressor or fluid pump comprises a substantially cylindrical housing 1, having an open flanged end, which is closed by a cover 2. The housing 1 has a closed end 3, as shown in Fig. 2, upon which is integrally therewith mounted an eccentrically located, bored hub 4, in which one end of a shaft 5 of a rotor 6 is rotatably mounted. The shaft 5 extends outwardly in one direction from the hub 4, and is slotted with a key slot 7, which may be used for a driving connection with a keyed driving member, not shown.

As shown in Fig. 3, the rotor shaft 5 may be bored lengthwise thereof, as at 8, to form a driving bore, across which are driven three pins a, a, a, to hold in place a drive shaft, not shown.

The cover 2, is cylindrically shouldered, as at 9, to fit a circular opening in the finished face of the flange 10, Fig. 2, and is held to the rotor housing 1 in an air tight manner by a plurality of circumferentially located screws 11, two of which are shown in Fig. 2.

The cover 2, further, is provided with a manually closed outwardly extending housing 12, Figs. 2 and 7, the closing lid 13 of which is attached by screws 14 thereto, also in an airtight manner.

The housing 12 is bored to receive therein a hardened and ground ball ring 15, which is inset in said housing and held therein by a cover 13.

The rotor head 6 has thereon an outwardly extending, ball bearing shaft 16, which is dowelled thereto by means of an integral flange 16a, Fig. 2, and has pressed thereon a hardened and ground ball ring 17, between which and the ring 15, are inserted a plurality of balls 18, thus to form a ball bear-

ing for the shaft 16 of the rotor 6 in alignment with the eccentrically located hub 4 and shaft 5.

The rotor 6, which is cylindrical and of a smaller diameter than the housing bore 19, is thus eccentrically located in said bore 19, as best illustrated in Fig. 1. The rotor 6 is further axially slotted across its full diameter thereof by a continuous blade slot 20, Figs. 1, 3 and 4, into which are mounted two closely fitted and ground blades 21-22. Normally, these blades, 21 and 22 in their working positions, as shown in Fig. 1, are spaced apart a distance 23, forming a pressure chamber.

The rotor 6 has arranged therein a pair of opposingly located air ducts 25-26, Figs. 1 and 4, these ducts being radially located forwardly of each blade 21-22, and the inner open ends 27-28 of said ducts 25-26 enter the blade slot 20 beyond the center of the rotor 6, this being best indicated, in Fig. 4, and thus cause the blades 21-22 to be constantly pressed outwardly, under air pressure, during the running of the pump, doing away with springs, and causing the blades ends to be engaged with the wall 19 of the pump, in direct proportion to the pressure within the pump, during operation thereof, which is an advantage. Also, the side thrusting means for the blades is an important function, since a seal is thereby formed on opposite sides of the slot 20, that is to say between the boundary faces of the slot and the flat sides of the blades, to prevent escape of fluid along the said sides and through the chamber 23. This function eliminates retarding influences in the operation of the pump.

The outer ends of the ducts 25-26 are open at the periphery 29 of the rotor 6 and at their intermediate parts, as at 30-31, are controlled by ball valve means, comprising spring seats 32-32, which are formed each by an enlargement of an intermediate portion of the ducts 25-26, upon which seats are located compression springs 33-33, which hold check balls 34-34 against bored ball valve plugs 35-35, which are threaded-ly mounted in enlarged outer portions of the ducts 25-26. As thus constructed, the ball valve assembly at each duct 25, 26, thus described, permits ingress of compressed fluid to and behind the blade spaces 23, but prevents escape of said fluid therefrom.

To provide an entry into the blade slot 20 to cause the blades 21-22 to be continually pressed against the sides of said slot during the operation of the rotor, the blades, as indicated in the perspective view thereof, in Fig. 5, are provided each on the side thereof with an air groove 36, which is of sufficient length to permit a full stroke of each of the blades 21, 22 during the rotation of the rotor 6; and said grooves, being located on the

sides of the blades 21, 22, which are nearest the ends of the inner duct ends 27-28, they prevent the blades 21-22, during their reciprocal movement, from cutting off any fluid pressure from entering to the spaces 23, and keep said spaces always in communication with said duct ends 27, 28, thereby also pressing said blades against the sides of said slot 20 as hereinbefore mentioned.

During the operation of the fluid pump, 75 when the rotor 6 rotates in the direction of the arrows A, Figs. 1 and 4, a suction is created in the space B, behind the blade 21, whilst a fluid pressure is created in the space C in front of the blade 21. On the suction side 80 the chamber B is constantly supplied with fluid, such as atmospheric air, through the inlet port 37 in the cover 2, Figs. 6 and 9, there being a coacting portion of said port 37 extending into the housing 1, as at 38, Fig. 1. 85 This latter portion 38, is of only a slight depth axially, whilst the cover 2, Fig. 6, has the greater portion of the inlet port 37 enclosed therein; this latter portion 37 is formed with an offset wall 39 contouring said inlet 90 port 37, as shown in Fig. 6, and has therein an opening 40 leading to atmosphere.

The fluid, which is compressed in the space C, is discharged through a port 41 in the cover 2, as shown in Figs. 6 and 8; the discharge port 41 extends as 42 into the body of the housing 1, as shown in Fig. 1, and terminates in said cover 2 in a discharge duct 43, which is exteriorly threaded at the outer end thereof, as shown in Fig. 7, and embodies 100 therein a valve seat 44, and cage 45, enclosing a check valve 46, as shown in dotted lines in Fig. 7.

I claim as my invention and desire to secure by Letters Patent:

1. In a rotary fluid pump or compressor, a housing, a rotor eccentrically positioned therein to have relative rotation therewith, a slot extending entirely through said rotor, blades, slidably mounted in said slot, in contact with the inner periphery of said housing, a means for producing said relative rotation, thereby forming a fluid pressure space in said pump, and a duct in said rotor, to convey compressed fluid from said space to one side of each of said blades, to press the same flatwise thereof against the sides of said slot in said member, thereby preventing leakage of compressed fluid therethrough.

2. In a rotary fluid pump or compressor of 120 housing, a slotted member, eccentrically positioned therein, to have relative rotation therewith, blades, each having therein a side groove and slidably mounted in said slot, in contact with the inner periphery of said housing, a means for producing said relative rotation, thereby producing a fluid pressure space and a suction space in said pump, a duct in a part of said member, to convey compressed fluid from said pressure space to the said grooves 130

in one side of each of said blades, to press the same flatwise thereof against the sides of said slot in said member, and a means on said duct to check the escape of compressed fluid therethrough to the suction space when said part 5 is adjacent the latter during the said relative rotation.

3. In a rotary fluid pump or compressor, a housing, a rotor eccentrically positioned therein, to have relative motion therewith, a slot extending entirely through said rotor blades, having each a side groove and slidably mounted in said slot, and in contact with the inner periphery of said housing, a means 10 for producing said relative rotation, thereby producing a fluid pressure space and a suction space in said pump, a duct in a part of said rotor, to convey compressed fluid from said pressure space to said grooves in one 15 side of each of said blades, to press the same flatwise thereof against the sides of said slot in said member, and a check valve on said duct, to prevent the escape of compressed fluid therethrough to the suction space when 20 said part is adjacent the latter during the 25 said relative rotation.

4. In a rotary fluid pump or compressor, a housing, a rotor eccentrically positioned therein, to have relative rotation therewith, a slot extending entirely through said rotor, a pair of blades, having side grooves and slidably mounted in said slot, with the outer end of each blade in contact with the inner periphery of said housing, a means for producing 30 said relative rotation, thereby forming a fluid pressure space in said pump, and a duct in said member, disposed to convey compressed fluid from a part of said space to the grooved side of each of said blades, in said 35 slot to press said blades flatwise thereof against the side of said slot in said member, thereby preventing leakage of compressed fluid therethrough.

5. In a rotary fluid pump or compressor, a housing, a rotary member eccentrically positioned therein, to have relative rotation thereto, a slot extending through said rotor blades, slidably mounted in said slot, and nor-

mally spaced one from the other but in contact with the inner periphery of said housing, thereby forming a fluid pressure space in said pump, a fluid pressure groove on one side of each of said blades and a duct in said member, to convey compressed fluid to said space and to said grooves, to press each of said blades flatwise thereof against the sides of said slot in said member, thereby preventing leakage of compressed fluid therethrough.

6. In a rotary fluid pump or compressor, a housing, a rotor having a cross slot therethrough, and eccentrically mounted to rotate in said housing, blades having each a groove in one side thereof and extending from the inner end longitudinally and centrally thereof for forming side pressure chambers; said blades being separated in operation, to form at their inner ends an axial pressure chamber in communication with said side pressure chambers; and means for driving said pump and for conveying compressed fluid to said pressure chambers for forcing the outer ends of said blades into operative engagement with the inner walls of said housing and for forcing the sides of said blades into sealing contact with the sides of said slot.

7. In a rotary fluid pump or compressor, a housing, a rotor having a cross slot extending entirely therethrough and eccentrically mounted in said housing, blades slideable free in said slot and spaced apart at their inner ends to form a pressure chamber of constant size and movable laterally across the axis of said rotor with the movement of said blades, said blades each having on one side a pressure groove communicating with the central pressure chamber whereby pressure received within said grooves may force the blades into sealing engagement with the walls of said groove, and valved ports for conveying fluid under pressure to said pressure chamber, and means for driving said rotor.

Signed at Charlottesville, in the county of Albemarle and State of Virginia, this 25th day of March, A. D. 1930.

JOHN R. PRICE.
